UNITED STATES PATENT OFFICE

NORMAN D. MATTISON, OF NEW YORK, N. Y.

FOOTWEAR

Application filed August 22, 1929. Serial No. 387,763.

This invention relates to shoes and other footwear (herein referred to as shoes) and more especially to the construction of the insoles of shoes.

5 It is the chief object of the invention to improve shoes and the insoles used in them with a view to promoting correct foot balance, inducing normal muscular action in the foot, and training the foot to correct habits.

10 In the accompanying drawings,

Figure 1 is a perspective view of a shoe embodying features of this invention, certain parts of the shoe being cut away;

Fig. 2 is a plan view of part of an insole 15 of the shoe shown in Fig. 1;

Figs. 3 and 4 are transverse sectional views through the shank portion of insoles constructed in accordance with this invention;

Fig. 5 is a diagrammatic view showing approximately the outlines of the plantar surface of a foot in balanced and pronated positions, respectively; and

Fig. 6 is a longitudinal section of one form of my invention.

25 Examination of a large number of feet has demonstrated that when a normal foot is in a balanced condition on a level surface the weight is supported on approximately that portion of the bottom of the foot indicated

30 by the area A, bounded by the dot and dash line Fig. 5. It will be observed that practically all of this area forward of the heel lies at the outer side of the longitudinal axis of the foot, indicated by the line B—C, and

35 that none, or at most very little, of the weight is borne by the surface under the inner end of the forward transverse arch, or, in other words, under the ball of the great toe joint. With the weight so distributed the muscular

40 action of the foot in walking is directed along approximately a line passing through the cuboid region F in what is sometimes called the "cuboid stream", and very little effort is directed along the "scaphoid stream", or inner longitudinal arch.

45 Examination of a very great number of defective feet shows that one of the most common foot defects and that often attributed to "arch trouble" of some kind, consists

50 of an inward rolling of the foot so that the

weight, instead of being distributed as above described, is partially shifted to the inner side of the longitudinal axis B—C. In this position the weight on the forepart of the foot is distributed over an area approximately like that bounded by the dotted line D, Fig. 5, and the outer longitudinal arch of the foot has risen somewhat, the degree of such rise depending largely on the peculiarities of individual cases. It may be such that no substantial part of the weight of the body rests on the plantar surface under the outer longitudinal arch, the weight being borne by the areas D and E, or there may be a shift of the weight on to arch surfaces lying inwardly, or toward the left, Fig. 5, of the area A. In a typical case there is a combination of these two actions, the weight on the cuboid region F, Fig. 5, of the foot being reduced to an undesirable degree, accompanied by a considerable shift of the weight inwardly.

55 The foregoing description refers more particularly to the conditions obtaining when a person is standing on both feet but much the same conditions are found in the distribution of weight in correct and faulty feet during the act of walking. A normal foot in correct balance with both the heel and forepart on the ground during the act of walking carries most of the weight on approximately the area A, Fig. 5, the pressure on the plantar surface of the forepart being much heavier at the outer side to the axis B—C, Fig. 5, than at the inner side, and very little pressure is exerted at this particular time on the great toe joint. As the heel lifts and the body progresses forward a shift of the weight occurs, the weight being delivered directly and evenly to the entire ball of the foot and the foot hinging evenly at the ankle 60 without inrolling. In a pronated foot with the heel and forepart resting on the ground during walking there is a decided shift of the weight (compared to the correct position) toward the inner side of the axis B—C, Fig. 5, and the pressures which should be external, or at the outer side of this axis, are exerted internal to it, the great toe joint 65 receiving pressure which should be borne by the cuboid region F. As the heel lifts and

70 75 80 85 90 95 100

the body progresses forward, an excessive part of the pressure comes on the great toe joint with a resultant irritation and undue strain on this part of the foot.

5 In all of these unbalanced conditions much more of the muscular effort is directed along the "scaphoid stream" and there is a decided deficiency in the proportion of the effort along the "cuboid stream". The presence of 10 bunions and callouses under the central portion of the forepart of the foot usually are indications of this faulty foot balance and incorrect distribution of weight.

The present invention proposes to 15 overcome these difficulties by creating a consciousness of and a demand for proper balance.

I have found that this can be done by making the surface of the insole on which the 20 weight should bear, particularly in the shank, at a higher level than the part of the insole just inside said area. In other words, the portion of the shank surface of the insole on which the weight is placed by a normal 25 foot in proper balance is made higher than the adjacent portion immediately inside and on which no weight should be borne. The rearward part of the upper surface of the shank and the heel of the insole should be 30 substantially on the same level, as in most shoes, the level subsiding gradually as it extends forward to the forepart. This higher level of the weight bearing part of the insole may be produced by cementing a 35 pad or a thickening piece of felt, sponge rubber, leather, or other suitable material on the surface of the insole of the shoe, the pad having substantially the shape of that part of the area A, Fig. 5, at the rear of the line G.

40 A shoe having an insole of this construction is shown in Figs. 1, 2 and 3. This shoe may be made by any suitable method of manufacture, such as the McKay, Goodyear or stitch-down processes, the present invention 45 not being concerned with the method used. The insole 3 preferably is made of leather, and as shown in these figures includes a pad or thickening member 4 of substantially the outline above described and 50 of any suitable material cemented, sewed or otherwise secured to the upper surface of the insole.

Instead of using a pad or thickening member 55 the material of the insole may be cut away along the inner area of the shank, thus leaving the part under the outer longitudinal arch which is to take the weight at a higher elevation than the other parts of the shank. Such a construction is indicated at 3', Figs. 60 4, 5 and 6, which show a loose or "slip" inner-sole.

Whatever the construction used, the upper surface of the insole is divided longitudinally 65 through the shank and the adjacent portions of the heel and forepart to provide inner and

outer areas, both extending longitudinally of the insole, the outer area serving to support the entire plantar surface under the outer longitudinal arch of the foot, when the foot is in a balanced position, and the inner area 70 being free of weight and located at a materially lower elevation than the outer area. Preferably a fairly abrupt shoulder separates these areas and the surface of neither area is inclined laterally to any substantial degree. 75 In other words they are laterally level.

The wearer of a shoe constructed in this manner is made aware of whether his foot is in a balanced or inwardly rolled (pronated) position by the sensations produced in his 80 foot whenever it rolls inwardly to any substantial degree away from its normal and correct position. This difference in sensation is produced by the fact that the area through the shank and certain parts of the 85 heel and forepart, which should not take weight, are at a lower elevation than those areas which should bear weight. When the foot rolls into such a position as to shift the weight inwardly to any substantial degree, 90 the sensation of rolling off its support tends to make the foot correct its position automatically by reflex action, just as would be the case if the wearer were walking on a rail. If the raised portion is made of a material 95 such as felt, rubber, or other substance which creates a different tactile sensation from that of the upper surface of the insole, the action above described is even more pronounced. The construction is unique in that it tends to 100 make the act of walking unconscious so long as the foot position is correct and the muscular action normal, but causes any substantial inward rolling of the foot to create a sensation which makes the foot bring itself back 105 into a balanced condition again. The tendency, therefore, is to train the foot into proper habits and to create in the foot itself the demand for correct balance and normal muscular action. 110

Having thus described my invention, what I desire to claim as new is:

1. An inner sole member for a shoe including a shank portion having a relatively long, narrow laterally level area for supporting the plantar surface of the outer longitudinal arch of the foot in a balanced position, and an area extending longitudinally of the shank between its inner edge and said supporting area and located at a lower level than said supporting area, said supporting area being substantially non-resilient throughout and effective to normally maintain the foot spaced from said second area. 120

2. An inner sole member for a shoe including a shank portion having a relatively long, narrow laterally level area for supporting the plantar surfaces of the heel, forepart and outer longitudinal arch of the foot in a balanced position, and an area extending longi- 125 130

tudinally of the shank between its inner edge and said supporting area and located at a lower level than said supporting area, said supporting area being formed of material offering a uniform reaction or counter-pressure to the weight imposed by the foot and effective to normally maintain the foot spaced from said second area.

3. An inner sole member for a shoe including a shank portion having its upper surface divided along the central region thereof to provide inner and outer areas both extending longitudinally thereof, said outer area serving to support approximately the entire plantar surface of the outer longitudinal arch of the foot in a balanced position and said inner area being located at a materially lower elevation than said outer area and being formed by reducing the thickness of that portion of the shank extending from the inner edge of the member to the edge of the outer area, said areas being integral with the insole, and separated from each other by a shoulder.
- 25 4. A shoe including an inner sole having a surface to engage and support only the plantar surfaces of the heel, forepart and outer longitudinal arch when the foot is in a balanced position, said surfaces in the rearward part of the shank and the adjacent portion of the heel being on substantially the same level, the upper surface of the shank including an area extending longitudinally thereof between its inner edge and said supporting surface of the shank, located at a lower level than said supporting surface, and a relatively abrupt shoulder separating said areas in the shank portion of the insole.

NORMAN D. MATTISON.
